UNITED STATES PATENT OFFICE.

CHARLES W. BRAY, OF PITTSBURG, PENNSYLVANIA, ASSIGNOR TO AMERICAN TIN PLATE COMPANY, OF PITTSBURG, PENNSYLVANIA, A CORPORATION OF NEW JERSEY.

METHOD OF ROLLING BLACK PLATES OR SHEETS.

SPECIFICATION forming part of Letters Patent No. 767,731, dated August 16, 1904.

Application filed December 4, 1903. Serial No. 183,685. (No specimens.)

To all whom it may concern:

Be it known that I, CHARLES W. BRAY, of Pittsburg, Allegheny county, Pennsylvania, have invented a new and useful Method of 5 Rolling Black Plates or Sheets, of which the following is a full, clear, and exact description, reference being had to the accompanying drawings, forming part of this specification, in which—

10 Figure 1 is a longitudinal vertical section showing a heating-furnace and outlet arranged for carrying out my invention. Fig. 2 is a diagrammatic plan view showing a mill to which the heated plates pass from the furnace, and Fig. 3 is a diagrammatic side elevation.

15 My invention relates to the rolling of black plates or sheets, and more particularly their rolling in piles.

20 The object of the invention is to make the sheets as nearly uniform in size and shape as possible in order to assist in the matching operation and to reduce the amount of scrap.

To that end the invention consists in heating 25 the bars or blanks in piles of two or more in number, so that two or more of the rolled sheets will thus be heated to a substantially uniform extent and will elongate to approximate the same amount.

30 In the drawings, 2 represents a continuous heating-furnace through which the sheet-bars are pushed, the bars resting upon side ledges and being moved forward by water-cooled bars 3, which are raised and lowered and 35 moved endwise in feeding the bars forwardly. The bars enter through the opening 4 and are ejected by the portions 5 of the bars 3. Instead of heating these bars in a single row I pass them through the furnace in piles of two 40 or more in number. Thus I have shown the furnace as containing the plates in piles of three. As the bars 3 rise and move forward in feeding the piles forwardly the portions 5

force out the front pile of plates, which pile slides down the outlet-chute 6 and drops upon 45 the feed-rollers 7. The feed-rollers carry the plates sidewise to the entering feed-table 8 of the rolling-mill, which is shown as of tandem form. The plates are drawn apart on the feed-table and fed forwardly singly and successively through the successive sets of rolls 9, 10, 11, 12, and 13 and then pass into the matcher 14. In this matcher the rolled sheets are squared up sidewise and endwise, and the pack is then fed forward through succeeding 55 sets of rolls 15 and 16.

The advantages of my invention result from heating the bars to be rolled in piles. This gives a substantially even heat to two or more of the plates, so that as they pass through the 60 rolls they will elongate to approximate the same extent. As the rolled sheets or plates from these bars are matched up, they will match more evenly and with less waste than heretofore, where the sheet-bars were heated 65 singly and separately. The shearing of the finished sheets will cut off less material than formerly, and the saving in scrap is found to be considerable.

The heating-furnaces, the mill employed, 70 and the method of heating and rolling may be varied without departing from my invention.

I claim—

1. The method of rolling black plates or sheets, consisting in superimposing two or 75 more bars to form a pile, moving the piles successively through a continuous heating-furnace, separating the bars, rolling said bars separately and successively, and then forming the separately-rolled plates into a pack; substantially as described.

2. The method of rolling black plates or sheets, consisting in superimposing bars to form a pile, feeding said pile through a continuous heating-chamber, separating the bars 85 of the pile and rolling the bars separately and

successively by passing them through successive tandem passes, and then matching the plates thus rolled; substantially as described.

3. The method of rolling black plates or 5 sheets, consisting in superimposing bars to form a pile, feeding said pile through a continuous heating-chamber, separating the bars of the pile and rolling the bars separately and successively by passing them through succes-

sive tandem passes, then matching the plates to thus rolled and then further rolling the matched pack; substantially as described.

In testimony whereof I have hereunto set my hand.

CHARLES W. BRAY.
